United States Patent Office.

SIMON SCHEUER AND ISAAC SCHEUER, OF NEW YORK, N. Y.

Design No. 2,719, dated August 6, 1867.

DESIGN FOR A POCKET-BOOK.

The Schedule referred to in these Letters Patent and making part of the same.

TO ALL WHOM IT MAY CONCERN:

Be it known that we, S. SCHEUER and ISAAC SCHEUER, of the city, county, and State of New York, have invented a new and improved Design for Pocket-Books; and we do hereby declare that the following is a full, clear, and exact description thereof, reference being had to the accompanying drawing, forming part of this specification.

The drawing represents a front view of our pocket-book.

The invention consists in ornamenting the corners of the front or covering-flap of the pocket-book, by rounding the same off, and by fitting over them a metallic plate or corner, which is consequently raised above them slightly, and made of a form to be hereinafter described, with rosettes and beads formed in low relief upon their upper or outer sides.

A represents the front flap of a pocket-book, with its corners rounded off, and having fitted over them by any suitable means the corners or plates B. These corners are rounded upon their outer sides, to correspond with the corners of the flap, and their inner edges are scalloped in curvilinear lines, as shown in the drawing. Upon the upper surface are formed, in low relief, rosettes a, the larger one being in the centre, or nearly so, with lesser ones upon either side. Beads b are also formed in low relief, at a short distance from and parallel with the inner edges c, as fully shown in the drawings.

We claim as new, and desire to secure by Letters Patent—

The design or pattern for pocket-books, substantially as herein shown and described.

SIMON SCHEUER,
ISAAC SCHEUER.
